(57) **CLAIM**

The ornamental design for a grilling utensil, as shown and described.

DESCRIPTION

FIG. 1 is a bottom, left, front isometric view of a grilling utensil showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a top view thereof, showing the claimed design with the occluding environmental lines removed.

FIG. 8 is a bottom view thereof.

FIG. 9 is a bottom view thereof, showing the claimed design with the occluding environmental lines removed.

FIG. 10 is a bottom, left, front isometric view of a grilling utensil showing our new design.

FIG. 11 is a bottom, left, front isometric view of another grilling utensil showing our new design; and,

FIG. 12 is a bottom, left, front isometric view of yet another grilling utensil showing our new design.

The dot-dash broken lines immediately adjacent the shaded areas represent the bounds of the claimed design, while all other broken lines are directed to environment and are for illustrative purposes only; the broken lines form no part of the claimed design.
